No. 790,367.

PATENTED MAY 23, 1905.

A. HOLLINGER.
RAILWAY CROSSING.
APPLICATION FILED MAY 9, 1904.

UNITED STATES PATENT OFFICE.

ANDREW HOLLINGER, OF CANTON, OHIO.

RAILWAY-CROSSING.

SPECIFICATION forming part of Letters Patent No. 790,367, dated May 23, 1905.

Application filed May 9, 1904. Serial No. 207,137.

To all whom it may concern:

Be it known that I, ANDREW HOLLINGER, a citizen of the United States, residing at Canton, in the county of Stark and State of Ohio, have invented a new and useful Railway-Crossing, of which the following is a specification.

This invention relates generally to railway-crossings, and particularly to that type of such crossings wherein a continuous rail is provided for the train which has the right of way.

The objects of the invention are to improve, simplify, and strengthen the construction of such crossings.

To these ends the invention resides in certain details of construction and novel combination of parts, as hereinafter described in detail, with reference to the accompanying drawings, forming part of this specification.

The invention particularly resides in novel means for permitting lateral movement or play of the bevel-ended rail-sections as they slide upon each other.

Referring to the drawings, Figure 1 is a plan view of a railroad-crossing constructed in accordance with the invention. Fig. 2 is a side view showing the eccentric arrangement for operating the rail-sections.

In the drawings the numerals 1 1 indicate parallel rails of a railroad-track extending in one direction, and the numerals 2 2 indicate similar parallel rails crossing the rails 1 1 at a right or acute angle, as may be required by the nature of each particular crossing to which the invention is applied.

Between the ends of the rails 1 1 are slidably mounted the rail-sections 3 3 and 4 4, the adjoining ends of which are beveled, as shown, in order that the rail-sections may slide longitudinally upon each other to open or close the rail-crossing. It will be understood that the rail-sections 3' 3' and 4' 4' between the ends of the rails 2 2 are precisely similar in construction to the rail-sections 3 3 and 4 4, and therefore a description of the latter sections will suffice also for the former. Extending transversely across the line of tracks 2 2 is an operating-rod 5, which is provided at one end with a lever or switch-arm 6.

Rigidly mounted upon the rod 5 are four eccentric cams 7 7 and 8 8, the cams 7 7 being adapted to operate the rail-sections 3 3 and the cams 8 8 the rail-sections 4 4. Arms 9 9, having eyes encircling the eccentric cams 7 7, 55 are pivotally connected at 10 10 by means of bolts or the like to the rail-sections 3 3, and similar arms 11 11, having eyes encircling the cams 8 8, are pivotally connected at 12 12 to the sections 4 4. The arrangement of the 60 cams 7 7 and 8 8 upon the rod 5 is such that when the rod is turned in one direction by means of the switch-lever 6 the rail-sections 3 3 and 4 4 are drawn toward each other and when the rod is turned in the opposite direction the rail-sections are moved away from each other.

If desired, an eccentric cam 13 may be mounted upon the rod 5 to actuate a rod 14, connected at one end to an angle-lever 15, 70 which operates a derail 16.

The operation of the crossing is as follows: When it is desired to give the right of way to a train on the tracks 2 2, the switch-lever 6 is turned in such manner that the rail-sections 75 3 3 and 4 4 are forced apart to close the gaps between the ends thereof and the rails 1 1, and the switch-lever 6' is turned in such manner that the rail-sections 3' 3' and 4' 4' are drawn together to open gaps adjacent to 80 the rails 1 1, as will be understood.

In constructing railroad-crossings with beveled rail-sections which slide upon each other to open or close the gaps in the rail a great disadvantage is caused by the lateral 85 widening or spreading of the rail-sections at their beveled meeting portions as they slide toward each other. In order to permit this widening or spreading of the rail-sections, they must be mounted in bearings that are 90 as wide as the greatest breadth reached by the two rail-sections when slid toward each other. Then when the rail-sections are slid apart to close the gaps in the rail they become narrower and are liable to rattle or be- 95 come displaced in their bearings, which are a trifle too wide for them when they are slid apart. It has been proposed to remedy this disadvantage by providing springs to hold the rail-sections together. This method, 100

however, is defective in that the springs are liable to give when a train passes over the rail-sections and by so giving to cause an accident. It is one of the prime objects of the 5 present invention to avoid the disadvantage above set forth with regard to the widening of the sections. In order to compensate for this widening, the rail-sections 3 3 are mounted to slide longitudinally in bearings formed 10 by bolts 17, set into the base-plate 18 of the device and fitting over the side edges of the rail-sections. The bolts 17 are set closely against the sides of the rail-sections, so as to prevent any lateral play thereof, the rail-sections 3 3 being permitted to move only in a longitudinal direction. The rail-sections 4 4 are mounted to slide on the base-plate 18 between bolts 19, similar to the bolts 17. On 15 one side each of the rail-sections 4 4 is formed 20 with two notches 20 20, one adjacent to each bolt 19 on that side of the rail-section. The long inclined wall of each notch 20 is parallel with the beveled end of the rail-section 4. For this reason as the rail-sections 3 3 and 25 4 4 are drawn together the bolts 19 enter the notches 20 at the same time that the beveled faces of the rail-sections slide upon each other. The result is that the rail-sections 4 4 move laterally with respect to the rail-sections 3 3. 30 Then as the rail-sections are forced apart to close the gaps in the rail the bolts 19 slide along the inclined walls of the notches 20 and force the rail-sections 4 4 tightly into position in a direct line with the sections 3 3. 35 Any rattling or liability of displacement of the rail-sections is effectually avoided in this manner.

It will be understood that changes in the details and particular arrangement of the 40 device may be made within the scope of the following claims without departing from the spirit of the invention. For instance, instead of forming the notches 20 only in the rail-sections 4 4 similar notches may be made in the

rail-sections 3 3, so that both sets of rail-sections will move laterally. In this event the notches in each section need be only one-half as large as those illustrated, for the reason that the number of notches will be doubled.

Having thus described the invention, what 45 is claimed is—

1. A railroad-crossing having slideable rail-sections formed with beveled meeting ends and notches formed with inclined walls parallel with the beveled ends of the sections. 55

2. A railroad-crossing comprising base-plates, and beveled-ended rail-sections slideably mounted thereon, the rail-sections having notches formed with inclined walls parallel with the beveled ends of the sections. 60

3. A railroad-crossing comprising base-plates, bolts thereon, and two sets of beveled-ended rail-sections mounted on the base-plates between the bolts, one set of rail-sections having notches formed with inclined walls parallel with the beveled ends of the sections. 65

4. A railroad-crossing having rail-sections, non-resilient means adapted to compensate for lateral movement of the rail-sections, an operating-bar extending transversely across the rail-sections and eccentric means on the bar for causing endwise movement of the rail-sections in opposite directions. 70

5. A railroad-crossing having rail-sections, non-resilient means adapted to compensate for lateral movement of the rail-sections, a switch-bar extending transversely across the rail-sections for moving them in opposite directions, and a derail operated by the switch-bar. 75

In testimony that I claim the foregoing as my own I have hereto affixed my signature in the presence of two witnesses.

ANDREW HOLLINGER.
